SKI

Ferdinand Alexander Porsche, Doeppingen, Germany,
assignor to Dr. Ing. h.c.F. Porsche Aktiengesellschaft

Filed July 31, 1972, Ser. No. 276,303

Claims priority, application Germany Jan. 29, 1972

Term of patent 14 years

Int. Cl. D21—02

U.S. Cl. D34—14 D

FIG. 1 is a top plan view of a ski showing my new design;

FIG. 2 is a modified form of the design shown in FIG. 1;

FIG. 3 is a side elevational view of the ski of FIG. 1, the side opposite being substantially identical;

FIG. 4 is a bottom plan view thereof;

FIG. 5 is a front elevational view thereof; and

FIG. 6 is a rear elevational view thereof.

I claim:

The ornamental design for a ski, as shown and described.
